UNITED STATES PATENT OFFICE.

CHARLES A. LARE, OF EUGENE, OREGON.

COMBINED CONTACT AND ENLARGING PRINTER.

1,273,881.

Specification of Letters Patent. Patented July 30, 1918.

Application filed May 31, 1917. Serial No. 172,028.

To all whom it may concern:

Be it known that I, CHARLES A. LARE, a citizen of the United States, residing at Eugene, in the county of Lane and State of Oregon, have invented certain new and useful Improvements in Combined Contact and Enlarging Printers, of which the following is a specification, reference being had to the accompanying drawings.

10 This invention relates to photographic appliances, and particularly to a photographic printing machine.

The general object of this invention is the provision of a photographic printing machine wherein a number of different printing operations may be performed.

A further object is to provide a printing machine which may be used either for contact printing or for enlarging or reducing.

20 Still another object is to provide a printing machine of this character which is particularly convenient in operation and which is vertically disposed, instead of horizontally disposed, so that the upper end of the 25 machine, which upper end is provided with ground glass, forms practically a table upon which the sensitized paper may be disposed, thus permitting the operator to stand beside the operating camera and readily manipulate the sensitized paper thereon.

30 A further object is to provide a construction of this kind which is adapted to be used either with incandescent lamps, arc lights or daylight as the source of illumination.

35 Another object is to provide a construction wherein the lamps are used in "contact" printing, may be adjusted nearer to or farther from the ground glass upon which 40 the negative and sensitized paper are disposed.

45 A further object is to provide, in a printing machine, a lens carrier which is vertically adjustable, and further in this connection to provide a vertically shiftable lamp and lens carrier which is provided with a non-actinic shutter and provide means whereby the non-actinic shutter may be operated.

50 Still another object is to provide a vertically shiftable lamp carrier having a plurality of lamps, one of the lamps giving a non-actinic light, and the other lamps producing an actinic light and provide means

whereby the non-actinic lights may be de- 55 energized coincidently with the energizing of the actinic lights.

A further object is to provide a hinged top which is, of course, opaque and which may be turned down upon the negative and 60 the sensitized paper supported on the ground glass and provide means whereby the closing of this top will automatically de-energize the non-actinic lamp and energize the actinic lamps.

65 A further object is to provide a non-actinic shutter and provide means for shifting this shutter out of operative position when the top or cover of the machine has been closed upon the sensitized paper.

70 A further object of the invention is to provide a vertically adjustable negative carrier which is adjustable toward or from the ground glass supporting the sensitized paper, and further to provide an adjustable 75 negative carrier and an adjustable lens carrier, thus permitting negatives to be enlarged to any desired extent and permitting the lens to be properly focused with relation to the negative.

78 Still another object is to provide in connection with the adjustable negative carrier, holders for diffusing screens, these holders being movable with the negative carrier.

85 Still another object is to provide a printing lamp mounted upon and adjustable with the negative carrier but provide means whereby the printing lamp may be adjusted independently upon the negative carrier.

80 A further object is to provide means 90 whereby the negative may be properly centered or laterally adjusted to any desired position upon the negative carrier.

95 A still further object is to provide a vignette supporting frame disposed beneath the ground glass at the upper end of the printing machine and provide means whereby the frame may be adjusted toward or from the ground glass.

100 Another object is to provide a reflector vertically adjustable toward or from the negative supporting frame, whereby border tints of varying qualities may be secured.

105 Another object is to provide means whereby the vignette supporting frame may be vertically adjusted or canted to secure various effects.

Still another object is to provide means

whereby negative back grounds, vignettes, and diffusing screens may be supported below the negative carrier.

Still another object is to provide means whereby the various lenses may be supported between the negative carrier and the ground glass upon which the sensitized paper is laid and in this connection provide means whereby the light diffusing screen used in making border tints may be shifted into an inoperative position around the lens carrier.

Still another object is to provide means for supporting a roll of moving picture film upon the film carrier and provide means whereby the film may be shifted to bring any desired picture into position to be enlarged.

Another object is to provide improved means for supporting a mat above the moving picture film, this permitting the mat to be shifted to bring openings of different shapes opposite the picture.

Other objects will appear in the course of the following description.

My invention is illustrated in the accompanying drawings, wherein:

Figure 1 is a front elevation of a photographic printer constructed in accordance with my invention;

Fig. 2 is a side elevation of the construction shown in Fig. 1;

Fig. 3 is a side elevation of the printing machine looking toward the side opposite that shown in Fig. 2;

Fig. 4 is a transverse vertical sectional view through the machine illustrated in Figs. 1, 2 and 3.

Fig. 5 is a section on the line 5-5 of Fig. 4, the section being on an enlarged scale;

Fig. 6 is a side elevation partly in section of the lower end of the printing machine, showing the manner in which the rear door is shifted in order to reflect light upward into the machine;

Fig. 7 is a sectional view through a portion of the negative supporting member showing means for supporting a roll of films beneath the lens;

Fig. 8 is a top plan view of the construction shown in Fig. 7;

Fig. 9 is a diagrammatic view showing the manner in which an enlargement is made in my machine, the figure showing the completed enlargement and the several mats, borders, masks, negatives, etc., used with the device;

Fig. 10 is a perspective view of the frame 60 99; and

Fig. 11 is a perspective view of the reflector 92.

Fig. 12 is a side elevation of the casing 42 or lens box showing the switch for energizing and deenergizing the lamps 40 and

41, the box being partly in section to show the shutter 45.

Referring to these figures, 10 designates a vertically extending casing which is illustrated as rectangular in form and provided at its upper end with a sheet of ground glass, designated 11. Of course, this casing is made light proof, in any suitable manner. The top of the casing is open above the ground glass 11, which ground glass is supported in place in a suitable frame and may be reversed, if desired, which will be later explained, and hingedly attached to the top of the casing and adapted to extend over the ground glass is a top, designated 12. This top is preferably made in a plurality of sections 13, 14 and 15. The section 13 is immediately hinged to the top of the casing by means of the hinge 16 and this section 13 is hinged to the relatively narrow section 14, by means of the hinges 17. The section 15 and the section 14 are beveled on their confronting edges and hinged on their under face. These hinges 18 are covered by the felt 19 which covers the under face of the top. A handle 20 is hinged at its rear end to the section 13 and extends over the forward edge of the top and is connected thereto by a metallic strap 21, through which the handle loosely passes. The handle is provided with a detent latch 22 engaging the keeper 23, mounted upon the front wall of the casing 10. This detent latch 22 is provided with a handle 24, whereby it may be disengaged from the keeper 23, so that the handle may be raised. It will be seen that the connection illustrated causes the various sections 13, 14 and 15 to take the position shown in Fig. 3 when the top is raised, but to take a position covering the upper end of the casing 10 when the handle is in the position shown in Fig. 2. The section 13 has a downwardly and forwardly beveled face and the section 14 has an upwardly and rearwardly beveled face, as shown in Fig. 3, and thus when the section 14 is lowered, the section 14 will close without rubbing against and moving the masks or sensitive paper on the ground glass 11.

The hinges between the section 15 and the section 14 permit the section 14 to be closed upon a portion of the sensitized paper or mats or both, while the hand is still holding them in the proper place and thus holds them securely while the hand is being removed. Then the section 15 is lowered in the manner before stated. The hinge 16 is preferably provided with a spring 25 which urges the top upward when the handle is released and when the latch 22 is released. Adjacent its lower end the front of the casing is provided with a relatively large door 26, and opposite this door, the back wall of the casing is formed with a hinged section 27, the outer face of which carries a reflec-

tor 28. This hinged section 27 is normally held in a vertical or closed position by any suitable latch, but may be turned down to the position illustrated in Fig. 6 when it is desired to use the reflector 28 as a means for throwing light up through the various lenses to the ground glass.

Slidably mounted within the casing 10 for vertical movement is a plate or platform 29, which is of photographically opaque material and which is adapted to carry a series of lamps and a lens. This carrier 29 has a portion 30, which projects out through a slot 31 formed in one side wall of the casing 10 and this portion 30 is connected to a vertically extending rack 32, disposed on the outside of the casing and which is of such length that it will, in all positions, close the slot 31. This rack 32 operates between two guide strips 33 mounted upon the wall of the box, these guide strips having overhanging flanges 34 attached to the guide strips by screws 35 and frictionally engaging the sliding rack 32 so as to hold the rack or slide 32 in any vertically adjusted position.

For the purpose of vertically adjusting the slide or rack 32, I provide a gear wheel 36, and a knob 37, which engages the shaft of the gear wheel. By rotating this knob it will be obvious that the slide will be raised or lowered and thus the carrier 29 will be raised or lowered. This carrier 29 is formed with a central opening 38 adapted to be closed by a door 39, which is also of photographically opaque material and mounted upon this door 39 is a non-actinic lamp 40. Also mounted upon the carrier 29 are a plurality of actinic lamps 41, shown as four in number. Carried upon the under face of the carrier 29 and extending downward therefrom, is a casing 42, formed with forwardly opening guides 43 adapted to engage with a lens 44. The lens 44 is removable from these guides so that various lenses may be engaged with the lens box 42. Disposed within this box or casing 42 is a shutter 45 of transparent material, colored, however, so that actinic rays will not pass through the shutter. This shutter is pivoted upon a spindle 46 whereby it may be rotated from a closed position to an open position. When it is closed, it extends across the upper end of the lens and prevents the passage of photographic light and when raised, it permits the passage of this light.

The purpose of these several lamps 40, 41 and the shutter will be later stated. The shutter is operated, however, by means of an arm 47, which in turn is connected to the extremity of a plunger 48 forming part of an ordinary cable release, the flexible tube of which is designated 49. This flexible tube extends out through the slot 31 and through the rack 32 and then extends upward and the upper end of the cable release tube is

supported adjacent the flange 50 formed on the top of the casing 10. The plunger 51 of the cable release extends through this flange 50 in such a position that when the top section 15 is fully closed, it will depress this cable release plunger and this will shift the arm 47 into a position to open the shutter 45. The lamp 40 is electrically connected by a wire 52 to a contact 53. The arm 47 is metallic and acts as a switch arm. The lamps 41 are connected in series on one side with a contact 54 and the other side of these lamps and of the lamp 40 is connected to a wire 55, and the switch arm 47 is connected to a wire 56. These wires 55 and 56 extend out through the member 30 to a socket 57, which in turn may be connected by a plug to an ordinary source of current. Now it will be seen that when the cable release is actuated by a closing of the top section 15, the shutter 45 will be opened and at the same time the arm 47 will be shifted to switch off the current from the non-actinic lamp 40 and switch on the current to the actinic lamps 41. The margin of the door 39 carries a contact 39^a coacting with a fixed contact electrically connected to the wire 55 and to the lamp 40.

Slidably mounted within the casing 10 below the carrier 29 is a second carrier 58. 95 This carrier, of course, fits the interior of the casing 10 and on one side is extended downward as at 59 for the purpose of supporting a lamp and reflector. The carrier 58 is formed with a central opening 60 and 100 with a plurality of longitudinally and transversely extending slots 61, whose purpose will be later stated. The depending sides of the carrier 58 are formed with a plurality of flanges 62 forming tracks at various distances from the carrier 58 in which diffusion screens, back-grounds, masks, etc., may be disposed.

This carrier 58 has a portion 63 which extends out through a slot 64 formed in the 110 side wall of the casing 10 and mounted between the guide strips 65 is a vertically disposed rack 66, which is held in place by the flanges 67, which flanges are held upon the strips 65 by means of screws 68 so that the 115 flanges may be caused to bear with greater or less friction upon the rack 66. One edge of the rack 66 is toothed to engage with a pinion or gear wheel 69, whose spindle carries a knob 70, thus permitting the rack 66 120 to be vertically adjusted and thus adjusting the carrier 58 to various vertical adjustments within the casing 10.

Mounted upon the depending portion 59 of the carrier 58 is an angular bracket 71, 125 the upwardly extending arm of which is slotted as at 72, a clamping screw 73 passing through this slot and permitting the bracket 71 to be vertically adjusted with relation to the carrier 58. Mounted upon this bracket 130

71 is an electric lamp 74 and surrounding this lamp is an upwardly directed reflector 75. This lamp is operatively connected by wires 76 to a socket 77 mounted upon the 5 rack 66, this socket being adapted to receive an ordinary plug leading from a source of electricity. It will thus be seen that the lamp 74 may be adjusted nearer to or farther from the carrier 58, but that as the carrier moves upward or downward, the lamp 10 will move upward or downward with it.

For the purpose of centering the negative, which may be disposed over the opening 60 in the carrier 58, I rabbet the upper face of 15 the carrier 58, as at 78 (see Fig. 5), and provide a frame 79, which is less in width than the opening 60 so that this frame may be laterally adjusted, this frame resting upon the rabbets 78. This frame is 20 rectangular in form and its upper face is rabbeted as at 80 and mounted within the frame 79 is a second frame 81, which is guided within these rabbets. This second frame has a length from front to rear less 25 than the depth of the frame 79, so that this second frame 81 may be adjusted at right angles to the movement of adjustment of the frame 79.

For the purpose of adjusting these frames 30 80 and 81 so as to properly center the negative, I mount upon the rack 66, a vertically disposed shaft 82, having a handle 83 at its upper end, this shaft extending downward to a point opposite the carrier 58 and being 35 there provided with a radially disposed arm 84. This arm is connected to the frame 79 by means of a link 85, pivoted to the arm and to the frame. For the purpose of shifting the frame 81, I provide the vertically 40 disposed shaft 86 having a handle at its upper end and having a radially disposed arm 87 at its lower end and mount upon the carrier 58, the bell crank lever 88, one arm of which is connected by a link 89 to the arm 45 87 of the shaft, the other arm being connected by a link 90 to the frame 81. It will be observed that the links 85 and 90 extend at right angles to each other and that a rotation of the shafts 82 and 86 will cause the 50 frames 79 and 81 to be shifted in directions at right angles to each other, though, of course, the movement of the frame 79 will carry the frame 81 with it. By this means, I can properly center any negative laid upon 55 the glass 91 which is supported by the frame 81 or bring any portion of the negative in coincidence with the axis of the lens 44.

Disposed between the carrier 58 and the carrier 29 is a reflector 92, which has a central rectangular opening 93, of such size 60 that it will accommodate the box 42 when this reflector is up against the bottom of the carrier 29. As shown in Fig. 11, this reflector has attached to its four corners, the 65 flexible connections 94, which pass over cer-

tain pulleys or eyes 95, these flexible connections all passing out through an opening 96 in the rack 32, then extending upward and being connected to a common cable 97 which, as illustrated, is wound upon a small spool 70 98 actuated by a finger knob. By rotating this spool in one direction or the other, the flexible connections 94 will be let out or taken up and the reflector 92 will be raised or lowered relative to the lens and relative 75 to the carrier 58. The slots 61 in the carrier 58 coat with this reflector in a manner which will be later stated.

Disposed in the upper portion of the casing 10 and vertically adjustable therein is a 80 vignette supporting frame 99, which is rectangular in form and provided with a central rectangular opening 100. This frame has attached to its four corners, the flexible connections 101, which extend upward and 85 extend over suitable pulleys or eyes to the exterior of the casing and are wound upon the spools 102, which are manually rotatable. By adjusting these spools, the vignette supporting frame 99 may be raised or lowered 90 and inasmuch as these spools are independently adjustable, the vignette supporting frame may be raised at one corner or at one end more than at other corners or at an opposite end, and thus the frame be canted to 95 secure certain effects, as will be later stated. A door 103 in the front wall of the casing 10 permits access to be had to this vignette supporting frame, this door being hinged to the wall of the casing and being held closed 100 by a latch 104. The front door 26 is also held closed by a latch 105.

One of the objects of this invention is to provide means for supporting a roll of moving picture films or a roll of other photographic films below the lens 44, so that the pictures on the roll may be enlarged and printed. To this end, I mount upon the frame 81, a pair of casings 106 and 107, 105 within which are provided spindles 108, each spindle being cleft to receive the extremity of a roll of film 109. The inner ends of the spindles 108 are supported by means of hinged brackets 110, hinged to the base 111 upon which the casings 106 and 107 are 115 mounted. Each of these members 110 is provided with a socket 112 adapted to receive the extremity of the spindle 108. This member 110 is held in a vertical position by means of the latch hooks 113. The confronting 120 faces of the casings 106 and 107 are formed with slots 114 through which the film passes and travels across the base 111. This base is, of course, provided with an opening 115. A mat may also be used in 125 connection with the films, such a mat being illustrated in Fig. 8 and designated 116, and being provided with a plurality of different sized and different shaped openings 117. This mat, which is in the form of a strip, 130

is held to the base 111 by means of guide clips 118, attached to the base 111, and projecting over the mat. It is thus an easy matter to shift the mat so as to bring any 5 desired form of mat 116 above the opening 115.

In the actual use of this invention for contact printing, the negative, either on glass or in the form of a film, is placed upon the 10 upper face of the ground glass plate 11. The image is visible through the negative by the actinic rays of the incandescent lamp 40. The bulb of this lamp is of a pale yellow color. The door 39 is, of course, closed. 15 The lamp carrier 29 may be raised or lowered to any desired distance from the ground glass plate 11. After the lamps have been properly arranged and the door 39 is closed so that the non-actinic lamp 40 is energized, 20 then the sensitized paper is placed upon the top of the negative on the plate 11 and the hinged top is brought down and this holds the sensitized paper in close contact with the negative and automatically switches the electric current from the non-actinic bulb 40 to 25 the actinic bulbs, by means of the cable release plunger 51. The picture is thus printed and is held in printing position so long as the top is closed but the moment the top 30 12 is raised, the current is switched back to the non-actinic lamp 40.

Masking may be done by placing a mask of the ordinary character on top of the ground glass 11 and the negative on top of 35 the mask, in order to secure sharp line masks but for soft line masking, the mask is laid on the swinging frame 99 and this frame 99 is raised by means of the spools 102 close up underneath the ground glass 11. Many 40 different soft or sharp effects may be made in this way and by reversing the ground glass 11 and placing the ground side downward, a further very soft and pleasing effect can be secured. Of course it is understood 45 that the mask referred to is the ordinary mask used in photographing, consisting of an ordinary sheet of paper or cardboard, the middle of which is cut out to permit the passage of light only through that portion of 50 the negative which it is desired to print.

Vignetting is done by placing the vignette paper or cardboard on the frame 99, then this frame is adjusted up or down according to the size of the picture desired or 55 the softness of the vignette wanted. It will be obvious, as before stated, that each of the spools 102 may be separately adjusted, thus tilting the frame 99 and the vignette to any angle desired for the purpose of blending 60 softer or sharper parts of the picture. Access may be had to the frame 99 by means of the door 103 and this permits the operator to place the vignette paper or cardboard on the frame 99 and adjust the same while its 65 image is visible on the ground glass 11.

To enlarge or reduce pictures and print them, the current plug is unscrewed from the socket 57 and engaged with the socket 77, or else the picture is printed by daylight or by the light of an outer lamp, as, for instance, an arc lamp. This is secured by removing the bracket 71 with the attached lamp 74 and turning the mirror 27 inward to such a position that light passing in through the opening in the back wall of the 75 casing will be deflected directly upward by the mirror. It will be understood that the different means of illumination above referred to do not in any way affect the operation or manner of adjusting the rest of the 80 mechanism.

In enlarging or reducing, the negative, in the form of a film or plate, is placed upon the carrier 58, the central opening 60 being covered by a plate of clear glass. After the 85 negative is placed upon the carrier, it being understood that the non-actinic shutter 45 is closed, the operator observes the picture formed upon the ground glass 11 and then by turning the knobs 70 and 37, he adjusts 90 the carriers 29 and 58 until the proper sized picture is secured upon the ground glass 11 and the picture is properly focused. It is to be noted here that the picture is plainly visible upon the ground glass 11 at all times. 95 Focusing may be done while the shutter 45 is closed, as this shutter is transparent and the image is plainly seen through the shutter. The shutter may be opened, however, by simply placing a light pressure of the fingers on the plunger 51. If the shutter is opened, then the shutter must be closed before the sensitized paper is placed upon the ground glass. After the sensitized paper is placed upon the glass 11, the exposure is 100 made by simply closing the top 12 and when the top is closed, the shutter is automatically opened by contact of the shutter with the plunger 51 of the cable release and this shutter remains open so long as the top 12 is 110 closed, but as soon as the top 12 is opened, the shutter closes. This method is followed in making a plain enlargement.

To make an enlargement with a white vignette, a vignette paper is disposed upon 115 a diffusing screen 119, which is disposed in any one of the guideways formed by the flanges 62 and beneath the carrier 58. This vignette paper is disposed at the center of the diffusing screen and over the light. The 120 operator then looks on the ground glass 11 and adjusts the negative, which is disposed upon the carrier 58 by shifting the shafts 82 and 86, then the exposure is made in the same manner as for a plain enlargement. 125 Any sized enlargement may be made by simply adjusting the carriers 29 and 58 toward or from each other and while this adjustment is being made, the operator may see the image on the ground glass, 130

To make any desired enlargement with a tinted border, a piece of thin white cardboard is cut about the size of the negative and in this cardboard is cut an opening having the desired shape, this opening being of a size to correspond to the portion of the picture which it is desired to print. This cardboard is then placed on the negative and the negative and cardboard mat so formed are disposed upon the negative carrier 58. The observer then looks upon the ground glass 11 and adjusts the carriers 29 and 58 to secure the size of enlargement desired and secure the proper focus. The spool 98 is then rotated to shift the reflector 92 and this reflector is moved up or down to produce the desired shade of the tinted border. This reflector acts by reflecting the light that comes through the openings 61 in the carrier 58 back upon the cardboard mats that are disposed upon or in proximity to the negative. During all of this time the operator sees everything on the ground glass 11. The exposure is then made as usual, but the picture will be printed with a tinted border around it, the shade of the tint being determined by the adjustment of the reflector 92.

This reflector 92 is a very important feature of my invention. It may be made of any material that will reflect to the best advantage. White cardboard forms a very good reflector, but bright and highly polished metal or glass mirrors are even better. The opening 93 in the center of the reflector 92 is large enough so that the reflector may be drawn up around the lens box 42 when not in use.

In order to print a white border around the tinted border, the machine is arranged as just previously described, but in a piece of opaque paper or cardboard, an opening is cut about the size of the white border wanted. This is disposed on the swinging frame 99. The operator then gazes upon the ground glass 11 and adjusts the picture by operating the shafts 82 and 86 and operating the spools 102 and then the exposure is made as usual, the result being a picture surrounded by a tinted band and around the tinted band there will be a white border.

For the purpose of printing back-grounds, where the original negative has no back-ground of any distinct character, a back ground negative is disposed on a piece of glass in turn disposed in one of the tracks formed by the flanges 62, this back ground negative being laid directly under the portrait negative and the small mat that is disposed on the carrier 58. The exposure is then made the same as usual, whereupon the picture will be printed with a background and the picture may be printed (on any desired enlarged scale) with a back ground, a

tinted border around the portrait, and a white border around the tinted border, all with one single exposure and with one source of light.

Any number of pictures may be printed from the same negative and with the same adjustment and all of the pictures be exactly alike, without any bother on the part of the operator or hurry for fear of the borders being moved or the borders being of different shades. Nothing comes in contact with the sensitive paper but the ground glass 11, on which the sensitive paper is laid and exposed by simply closing the top 12 once.

A variety of sizes of enlargement may be easily made by adjusting the carriers 29 and 58 and any desired shade of tinted border may be made by a slight adjustment of the reflector 92. A great variety of assorted shades or tints for borders may be secured by using different shades of paper to make the small mats that are placed near the negative and from which the light reflected from the reflector 92 is again reflected. Vignetting may also be done by the use of a reflecting mat placed upon the negative and reflecting the light cast downward from the reflector 92. The machine also operates particularly well for printing one or more heads out of a group negative and securing a tinted vignette to match the tint in the back ground in group negatives and all with one exposure.

The object of extending the lens box down below the carrier 58 is to permit the reflector 92 to be raised above the lens while using short focus lenses and enlarging from small negatives or films. Furthermore, when the reflector is raised to a position around the lens box, it affords room for the film holder formed by the parts 111, 106 and 107, which parts are adapted to contain a fifty foot roll of moving picture film. It will be seen that the film used need not be cut apart for the purpose of enlargement and with this device enlarged negatives may be made from positive films in the same manner as enlarged positives may be made from negatives, the only difference being that a slow light is used.

It will be noted that with the printing machine heretofore described, once the parts are adjusted, they will remain in adjusted position and hence any number of prints may be made, all exactly alike. Furthermore it will be seen that with this machine, the operator can see at all times exactly what is being done. He can secure just the enlargement he desires, he can accurately focus the lens upon the ground glass, and he can accurately set and register the various mats, masks, border framing reflector, and back grounds at a minimum of trouble and when these parts are set all of the effects

can be secured with one exposure. In other methods of printing borders, tints, back grounds, etc., it is necessary to use a plurality of exposures.

5 In Fig. 9, I show the manner in which the various negatives, masks, vignette papers, etc., are arranged within the printing machine in order to produce an enlargement having a background, having a tinted border 10 and having a light line or tint around the tinted border and having a back-ground border. In Fig. 9, the picture is designated *a*. This picture is a portrait and the negative from which the portrait is made contains no back-ground *b*. The enlargement, however, has a back-ground *b*. Surrounding the picture itself and the back-ground *b* is a tint *c* and defining this tinted margin is a light line *d* and surrounding the entire picture and separated from the tint *c* by the light line *d* is a border *e*. In order to produce this picture, a mask *e'* is arranged upon the swinging frame 99, as illustrated in Fig. 9, the sensitive paper *f* being disposed upon 20 the glass 11. Below the lens box and resting upon the negative carrier 58 is the negative *a'* and below the negative *a'* there is arranged the back-ground negative *b'*. Disposed about $\frac{1}{2}$ " above the negative *a'* are the 25 mats *c'* and *d'*. The mat *c'* is used for forming the tint *c* and the mat *d'* is used for forming the back-ground *e*, the mask *e'* being used to define the outer edge of this border.

30 35 It will be seen that Fig. 9 is purely diagrammatic and is merely for the purpose of illustrating how the various masks, negatives and mats are disposed within the machine.

40 45 In order to explain the action of the reflector 92, it may be said that if there were no openings 61 in the negative carrier 58, no light could get through from below to be reflected upon the small mats that lie upon the negative. Therefore, there will be no impression made upon the sensitized paper on the ground glass 11, at least no impression corresponding to the mat. No matter what color or how many colors or shades are 50 used, the result would be one white border around the picture representing the portion of the smallest mat and nothing more, but with the openings 61 in the carrier 58, a certain amount of light passes up through the 55 negative carrier from the light below and is reflected by the inner parts of the machine back upon the mats and is effective on the sensitized paper on the ground glass 11, in case the negative is very intense and requires a long time of exposure, but in case 60 the negative is weak, or a weak printer, there would not be sufficient light fall upon the mats in the short length of time required to make the picture, to have the desired ef-

fect upon a sensitized paper on 11 to tint the 65 border and, therefore, only a white border would be made. Hence the use of the reflector 92 and by raising or lowering this reflector, the amount of light directed upon the small mats may be governed more or 70 less, to correspond with the time of exposure, with different strengths of negatives, thus giving the desired tint to the border. This is one of the main features of my invention and is very simple and has been found thoroughly effective in practice. 75

While I have illustrated a construction which I have found to be particularly advantageous and particularly convenient and which does thoroughly effective work, yet 80 it will be understood that the device may be changed in many ways, without departing from the spirit of the invention. It is pointed out that one of the advantageous features of this invention resides in the fact that the 85 ground glass 11 is horizontal and that, as a consequence, the negative and the sensitized paper in contact printing, or the sensitized paper in enlarging are very readily adjusted from the ground glass and very readily held 90 in position, centered and otherwise manipulated. It will likewise be seen that the image of the negative, back-ground, masks, etc., are at all times cast upon the ground glass 11, so that the various manipulations may be 95 observed as they are made and that the sensitized paper disposed upon the ground glass may be adjusted to exact position, without any danger of being acted on by light because of the use of the non-actinic lamp 40, 100 which remains energized, with the actinic lamps 41 deenergized, just so long as the top of the machine is raised. It will further be obvious that the printing machine is adapted to be used with daylight or with an incandescent lamp 74, or that a source of light such as an arc light may be used in connection with the reflector or mirror 27. The machine is simple, compact, may be readily adjusted and will do a very large variety 110 of work, as before stated, and once the parts are adjusted to any certain condition, thereafter all the prints made from the negative will be exactly the same, which is not possible with other printing machines used for 115 printing photographs with borders, backgrounds, etc.

Having described my invention, what I claim is:—

1. A photographic printing machine including a vertically disposed casing, ground glass disposed in the upper portion of the casing, a lens support and a negative support disposed within the casing below the ground glass, the lower end of the casing 120 being formed with a section formed with a reflecting surface and adapted to be disposed within the lower part of the casing at an 125

- angle whereby light may be reflected through the opening in the casing and upward through the negative in the lens, said section forming one wall of the casing when in a closed position.
2. A photographic printing machine including a vertically disposed casing, a sheet of ground glass in the upper end of the casing, a lens support and a negative support disposed within the casing, and a source of illumination detachably mounted within the casing, one wall of the casing being formed with a hinged section movable inward into the casing, the outer face of this wall having a reflecting surface, the wall when moved inward acting to reflect light through the opening in the wall of the casing upward through said lens and negative.
3. In a photographic printing machine, a casing, a sheet of ground glass disposed at one end of the casing and forming a support for a sheet of sensitized paper, a lens mounted within the casing, a negative support mounted within the casing, a member having a light reflecting surface disposed between the lens and the negative support, the central portion of the member being cut out and the member having a reflective surface directed toward the negative support, means for directing rays of light through the negative and the lens, and means for causing the rays of light to be directed toward the reflecting surface of said member.
4. In a photographic printing machine, a casing, a sheet of ground glass disposed at one end of the casing and forming a support for a sheet of sensitized paper, a lens mounted within the casing, a negative support mounted within the casing, a member having a light reflecting surface disposed between the lens and the negative support, the central portion of the member being cut out and the member having a reflective surface directed toward the negative support, means for directing rays of light through the negative and the lens, the negative support being formed with openings through which light may be directed against the reflecting surface of said member.
5. In a photographic printing machine, a casing, a sheet of ground glass disposed at one end of the casing and forming a support for a sheet of sensitized paper, a lens mounted within the casing, a negative support mounted within the casing, a member having a light reflecting surface disposed between the lens and the negative support, the central portion of the member being cut out and the member having a reflective surface directed toward the negative support, means for directing rays of light through the negative and the lens, the negative support being formed with openings through which light may be directed against the reflecting surface of said member, said openings being arranged in parallel relation to the sides and ends of the negative support.
6. A photographic printing machine including a casing, a sheet of ground glass disposed in the casing and forming a support for a sheet of sensitized paper, a negative support mounted within the casing, means for directing rays of light through the negative mounted on said support and toward the ground glass, and means for reflecting rays of light downward around the margin of the negative.
7. A photographic printing machine including a casing, a sheet of ground glass supported on the casing and forming a support for a sheet of sensitized paper, a lens mounted within the casing and adjustable toward or from the ground glass, a negative supporting member mounted within the casing and independently adjustable in the casing, and a light reflecting member disposed between the lens and the negative support and independently adjustable toward or from the negative support.
8. A photographic printing machine including a casing, a sheet of ground glass supported on the casing and forming a support for a sheet of sensitized paper, a lens mounted within the casing and adjustable toward or from the ground glass, a negative supporting member mounted within the casing and independently adjustable in the casing, and a light reflecting member disposed between the lens and the negative support and independently adjustable toward or from the negative support.
9. In a photographic printing machine, a casing, a sheet of ground glass at one end of the casing and adapted to support a sheet of sensitized paper, a lens disposed within the casing, means for directing light through the casing toward the ground glass, a mask carrier disposed within the casing between the lens and the ground glass, and means for independently adjusting each corner of the carrier toward or from the ground glass.
10. In a photographic printing machine, a casing, a sheet of ground glass at one end of the casing and adapted to support a sheet of sensitized paper, a lens disposed within the casing, means for directing light through the casing toward the ground glass, a mask carrier disposed within the casing between the lens and the ground glass, means for independently adjusting each corner of the carrier toward or from the ground glass, said means including flexible connections attached to the corners of the carrier and supporting the same, and independently operable spools upon which the flexible connections are wound.

11. In a photographic printing machine, a casing, a sheet of ground glass at one end of the casing adapted to support a sheet of sensitized paper, a lens mounted within the casing, means for directing light through the lens and toward the ground glass, a negative carrier mounted between the source of light and the lens and including frames 5 slidable in directions at right angles to each other, and means for independently shifting said frames to thereby center a negative carried thereby.

12. In a photographic printing machine, a casing having a sheet of ground glass at one end to support a sheet of sensitized paper, a source of light at the other end of the casing, a lens supported within the casing, and a negative carrier disposed between the source of light and the lens, said carrier 15 having a central opening, a frame mounted in said central opening and movable in one direction across said opening, a second frame slidably mounted upon the first named frame for movement at right angles to the movement of the first named frame, and manually operable means extending out of the casing for independently shifting said frames.

13. In a photographic printing machine, a casing having a sheet of ground glass at one end for supporting a sheet of sensitized paper and having a source of illumination at the other end, a lens mounted within the casing, and a negative carrier disposed between the lens and the source of illumination, said carrier having a square opening at its center, a frame having the same depth as said opening, but less in width and movable transversely across the opening, said 35 frame being longer than it is wide, and a second named frame having a length less than the length of the first named frame but having the same width and having slidable engagement therewith, and manually operable means for shifting the frames upon each other and extending out of said casing.

14. In a photographic printing machine, a casing having a sheet of ground glass at one end for supporting a sheet of sensitized paper and having a source of illumination at the other end, a lens mounted within the casing, and a negative carrier disposed between the lens and the source of illumination, said carrier having a square opening at its center, a frame having the same depth as said opening but less in width and movable transversely across the opening, said frame being longer than it is wide, a second named frame having a length less than the length of the first named frame but having the same width and having slidable engagement therewith, and manually operable means for shifting the frames upon each other and extending out of said casing, said 60 means including shafts mounted upon the

casing and having cranks operatively connected to said frames.

15. In a photographic printing machine, a casing having a sheet of ground glass at one end for supporting a sheet of sensitized paper and having a source of illumination at the other end, a lens mounted within the casing, and a negative carrier disposed between the lens and the source of illumination, said carrier having a square opening 70 at its center, a frame having the same depth as said opening, but less in width and movable transversely across the opening, said frame being longer than it is wide, a second named frame having a length less than the length of the first named frame but having the same width and having slidable engagement therewith, and manually operable means for shifting the frames upon each other and extending out of said casing, said 80 means comprising shafts mounted upon the exterior of the casing and having crank arms, links extending through the casing, one of said links being connected to the first named frame, a bell crank lever having one arm connected to the other link, the other arm of the bell crank lever having link connection to the second named frame.

16. In a photographic printing machine, a casing, a sheet of ground glass disposed at one end of the casing and forming a support for a sheet of sensitized paper, a transparent negative support mounted within the casing, means for directing rays of light through the negative on the support and 90 against the ground glass, and a member having a central opening and having a light reflecting surface confronting the negative support, said member being disposed between the negative support and the ground glass, 100 the light rays reflected from said surface being reflected downward and forming a border around the picture formed upon the ground glass.

17. In a photographic printing machine, a casing, a sheet of ground glass disposed at one end of the casing forming a support for a sheet of sensitized paper, a negative support mounted within the casing and having a transparent sheet for immediately supporting the negative, the negative support being formed with slots bordering said sheet, means for directing rays of light upward through the negative support, and a reflector adjustable between the negative support and the ground glass and having a reflecting surface confronting the negative support.

18. In a photographic printing machine, a casing, a sheet of ground glass disposed at one end of the casing forming a support for a sheet of sensitized paper, a negative support mounted within the casing and having a transparent sheet for immediately supporting the negative, the negative support being formed with slots bordering said sheet, means 125

for directing rays of light upward through the negative support, a reflector adjustable between the negative support and the ground glass and having a reflecting surface confronting the negative support, and means for adjusting said reflector comprising a plurality of flexible connections, pulleys over which the flexible connections pass, a rotatable spool, and a connection leading from said 10 flexible connections to said spool.

19. In a photographic printing machine, a vertically disposed casing having a sheet of ground glass at its upper end, a top closing against said sheet and adapted to hold a 15 negative thereto, a vertically adjustable vignette supporting frame mounted below the ground glass and adjustable toward or from it, a vertically adjustable lens supporting carrier mounted within the casing below said 20 frame, a vertically adjustable negative supporting carrier mounted below the lens carrier, and having a transparent negative supporting sheet and having bordering slots, the negative carrier being formed below said 25 negative supporting sheet with a series of flanges upon which back-grounds, screens, etc., may be disposed, illuminating means carried by the negative supporting carrier, vertically adjusting racks mounted on the 30 sides of the casing and operatively connected one to the lens carrier and the other to the negative carrier, pinions engaging said racks whereby the racks may be shifted, a reflecting member disposed between the lens carrier 35 and the negative carrier and vertically adjustable, said reflecting member being cut out at its center and formed on its under side with a reflecting surface, means for adjusting said reflector, a shutter mounted on the 40 lens carrier and disposed above the lens carried thereby, the shutter being of transparent non-actinic material, and means for closing or opening the said shutter.

20. In a photographic printing machine, a 45 vertically disposed casing having a sheet of ground glass in its upper end adapted to support a sheet of sensitized paper, a top closable upon the top of the casing to hold the paper in place upon the ground glass, a vertically movable lens carrier mounted within the casing and having a central opening, a lens carried thereby, a plurality of actinic electric lamps mounted upon the carrier, said carrier having a central opening alining with 50 the lens, a shiftable door mounted upon the carrier and movable to cover or uncover said opening, a translucent color screen carried by the lens carrier disposed above the

lens, means for shifting said screen out of its position above the lens when the top is 60 closed down upon the top of the casing, said screen being shifted across the axis of the lens when the cover is open, means disposed upon the outside of the casing for vertically adjusting the lens carrier, a vertically adjustable negative support mounted below the lens support, means upon the exterior of the casing for vertically adjusting the negative support, and a lamp support mounted below the negative support. 70

21. A photographic printing machine including a casing, a sheet of ground glass supported thereon and forming a support for a sheet of sensitized paper, a negative carrier mounted in said casing for adjustment toward or from the sheet of ground glass, a lens carrier mounted in the casing between the negative carrier and the ground glass and independently adjustable toward or from the ground glass and toward or from the negative carrier, a lens mounted upon said carrier, a non-actinic shutter mounted in the lens carrier and normally disposed between the lens and the ground glass, a cover adapted to be disposed over the ground glass 80 to hold the sensitive paper thereon, and means actuated by the closing of the cover shifting said non-actinic shutter to an inoperative position. 85

22. A photographic printing machine comprising a casing having a sheet of ground glass in its top, a negative support mounted within the casing for movement toward and from the negative support, a mask support mounted below the sheet of ground glass and adjustable toward or from it, a lens support disposed between the mask support and the negative support and independently adjustable toward or from the sheet of ground glass, means for supporting back ground 95 negatives below the negative support, means for directing light rays upward through the negative support toward the ground glass, and a reflecting member disposed between the negative support and the lens support 100 and longitudinally adjustable with relation to both of said supports, said reflecting member reflecting light down upon the negative and having an open center. 105

In testimony whereof I hereunto affix my 110 signature in the presence of two witnesses.
